MARGINAL STOP FOR TYPEWRITERS OR
THE LIKE AND MECHANISM FOR SETTING
THE SAME

Seyed Khalil, New York, N. Y., assignor to Underwood Corporation, New York, N. Y., a corporation of Delaware

Application March 31, 1949, Serial No. 84,514

19 Claims. (Cl. 197—63)

1

This invention relates to improvements in marginal stops for typewriters or the like and mechanism for setting the same, and has for a principal object the provision in a typewriter, or other device employing a movable carriage, of marginal stops which are settable or adjustable in a more convenient and more nearly automatic manner.

In the accompanying drawings I have shown a preferred form of my invention for marginal stops and mechanism for setting the same, and a modification thereof. The preferred form is shown in Figures 1 to 12, inclusive, while the modified form is shown in Figures 13 to 16, inclusive.

The preferred form of the invention includes a controlling governor, which causes the marginal stop setting mechanism to operate automatically at the proper time in the adjustment procedure, thereby eliminating the necessity of certain sequential operations such as are required by similar devices of the prior art, which involve the operator's having to remember to take each and every sequential step at the proper time in the procedure.

The modified form of my invention requires more distinctly separated steps in the adjustment procedure.

The preferred form of my invention will be presently described.

Function of my margin setting mechanism

To more readily describe the mechanism of my margin setting invention, I shall first and briefly describe the functions of said mechanism for resetting my left and right hand marginal stops.

In my margin setting mechanism, as well as in many other margin setting mechanisms, the usual carriage feed mechanism must be released, that is the carriage must be released from the control of the escapement mechanism, before other operations for setting of said margin stops are carried out.

Many margin setting mechanisms of the prior art necessitate the use, in addition to one or more margin setting levers, keys, etc., of the usual carriage release lever to keep the carriage released during the procedure for setting either one of the marginal stops.

I use a single lever, which is designated Margin, for operating both the margin setting mechanism and the carriage release mechanism.

Said Margin lever, which also will be referred to as a margin setting control, is conveniently

located at the right end of the carriage and is adapted to be operated in the same manner as the carriage release lever is operated.

When said Margin lever or control is being depressed, it swings in two phases. In the first phase said Margin lever releases the carriage, while in a later, final phase it releases one or the other of the marginal stops from the marginal rack and enables the same to be reset at the desired position. However, as explained hereinabove, the later phase of operation is dependent on positioning the carriage first so that the marginal stop to be adjusted occupies a relation of engagement with a counterstop.

Although for margin setting purposes I release the carriage by said Margin lever, I retain the usual carriage release lever for conventional carriage positioning purposes.

While both the carriage release lever and the Margin lever will release the carriage from the escapement mechanism, the operation of the carriage release lever is independent of the Margin lever.

For convenience of manipulation of the machine, said carriage release lever is preferably mounted on the left end of the carriage, while said Margin lever is mounted on the right end of said carriage.

As described above, my Margin lever has a twofold action: first, it releases the carriage, and secondly, it operates my margin setting mechanism.

The dual function of my Margin lever renders my margin setting mechanism manipulative with a minimum of attention required by the operator.

For example, to set the left hand marginal stop by my invention, the Margin lever is depressed through a first phase of operation to release the carriage from control of its feed mechanism. Then the carriage is moved to the right until the marginal stop reaches a position of engagement with the stationary stop. With this position of the margin stop prevailing, the Margin lever is operated through the stated later phase to unlock the marginal stop from holding engagement on its supporting rack and to render it stationary. The carriage remains released from the feed mechanism and is then given the desired position at which said left margin stop is to be active, which automatically results in the desired repositioning of the marginal stop. Then said Margin lever is released and the marginal stop consequently becomes secured in the new position on the rack.

To set the right hand marginal stop, according to my invention, the carriage is released by the very same Margin lever; moved to the left until the right marginal stop reaches a relation of engagement with the counterstop; then moved to the left or the right to a position at which the marginal stop is to be active henceforth, and then the Margin lever is released. This automatically sets the right marginal stop.

From the above it will be seen that a single Margin lever is used, whether it is desired to set the left marginal stop, or the right marginal stop.

Also it will be seen that said Margin lever is depressed in a single direction for setting either the left or the right marginal stops.

Furthermore, it will be seen that no levers, keys, etc., other than said Margin lever, have to be used for setting either of said marginal stops.

My marginal stops

Each of my marginal stops, as is the case with some marginal stops of the prior art, includes two members, which will be termed outer member and inner member.

The outer member of each of my marginal stops slidably embraces the marginal rack, as does the outer member of some marginal stops of the prior art. The inner member of my marginal stop is pivotally mounted on the outer member of said stop on a short shaft, the axis of which is parallel to the direction in which the marginal rack extends.

Accordingly, the inner member of my marginal stop engages and disengages the marginal rack at a right angle to the length thereof, while the inner member of many marginal stops of the prior art engages and disengages said marginal rack in a direction at a right angle to the engaging direction of the inner member of my marginal stop.

The entering edge of the tooth on the inner member of my marginal stop is provided with an apex so that it readily re-enters between the teeth of the marginal rack.

Thus, my marginal stops engage the marginal rack more readily than do the marginal stops of the prior art and are consequently superior to the latter.

After having entered between two teeth of the marginal rack, the tooth of the inner member of my marginal stop, contacts said teeth of the marginal rack more firmly than does the tooth of the inner member of marginal stops of the prior art, due to the disadvantageous direction of movement of the inner member of the latter.

To each of the inner members of my marginal stops is secured an arm which is adapted to be engaged by my margin setting mechanism for swinging said member to disengage it from said rack, as will presently be described in this specification.

To each of my outer members is secured a "tripping leg" which is adapted to exercise such control over my margin setting mechanism that either marginal stop is only releasable from the rack if by carriage movement it is first brought into a relation of engagement with the counterstop, as will also be presently described.

A vertical slot is provided in my outer member of each marginal stop and is adapted to be engaged by my margin setting mechanism for maintaining said relation of engagement of the stop which is to be adjusted, said outer member,

together with its inner member, being held at a given position of the frame of the typewriter, as will be fully described in the course of this specification.

Mechanism of my margin setting invention

The mechanism of the preferred form of my margin setting invention will be presently described.

An element which is termed herein a "dog" is pivotally mounted on the frame of the typewriter in substantially lateral alignment with the stationary stop. A spring urges said dog upwardly against a limiting stop. The free end of said dog extends toward the rear of the typewriter, while the pivoted end of it is toward the front of the typewriter.

The margin lever carries a rod which extends from one end of the carriage to the other end thereof, and is normally in a position which is at a given distance above the surface of said dog. Said rod moves downwardly with the Margin lever so that when said Margin lever is depressed it releases the carriage from the escapement mechanism before said rod contacts said dog.

Substantially in lateral alignment with the stationary stop there is pivotally mounted on the frame of the typewriter a normally vertical column termed herein "controlling governor." A spring means constantly urges said governor to a position where its center line is vertical but from which position it is laterally swingable about its lower end.

The upper end of said governor is located beneath said dog if neither of said marginal stops approximates a position of engagement with the counterstop, there being a working clearance between the governor and the dog.

The carriage feed mechanism becomes released in a first phase of downward movement of the Margin lever and then said rod contacts said dog which however cannot move down if said governor stands in a blocking position therebelow due to the fact that neither marginal stop is in a position of engagement with the counterstop. Consequently, said governor initially restricts the movement of the Margin lever downwardly to effect only the release of the carriage feed mechanism unless said governor is displaced in a manner to be presently described.

On each outer member of the two marginal stops, as described in the preceding paragraphs, there is secured a "tripping leg."

Assuming the left marginal stop is well to the left of the counterstop and is desired to be adjusted, the operator will apply operating pressure on the Margin lever, thereby releasing the carriage for movement. Thus with operating pressure maintained on said lever, the carriage is moved toward the right, and the tripping leg of the left marginal stop will, at a position near the stationary stop on the frame, engage said controlling governor and displace it from beneath said dog toward the right, thereby allowing said dog to move then downwardly to release the margin stop.

When similarly the carriage is moved toward the left to set the right marginal stop, the tripping leg of said marginal stop will, at a position near the stationary stop on the frame, engage said governor and displace it from beneath said dog toward the left, thereby allowing said dog to move downwardly (as the operator continues to exert pressure on the Margin lever). As the dog

is moved downwardly in this manner, it enters into a slot in the marginal stop that is being set and contacts said arm of the inner member thereof, causing said inner member to swing about its pivot out of locking engagement with the marginal stop rack.

Each outer member of said marginal stop is, as described in the preceding paragraphs, provided with a slot in a location so that when either marginal stop is at rest against the stationary stop such slot is directly beneath said dog. Therefore, pressure on the Margin lever can cause the dog to enter the slot of either marginal stop for marginal stop releasing action only if the stop is in or assumes a relation of engagement with the counterstop. The dog entering a slot not only releases the marginal stop, as described, but it also prevents the marginal stop from being displaced with respect to the counterstop.

From the above it will be readily seen that when the carriage is thereafter moved to bring a desired future marginal point thereon in line with the center of the typing, the released marginal stop remains at the stationary stop under control of said dog. When the Margin lever is released, the dog swings upwardly to its normal position and the marginal stop is automatically relocked in the desired position on the marginal rack.

Modified form of my invention

The modified form of my invention is based upon the preferred form of my invention with the following variation:

The controlling governor and the tripping legs are eliminated in the modified form of my invention.

Said rod is adapted to normally be in close contact with said dog.

The Margin lever has no connection to release the carriage, and instead the carriage is released by the usual carriage release lever.

The operation of my modified form is as follows:

In order to set the left hand marginal stop, the carriage is released from the escapement mechanism, as usual, by depressing the carriage release lever with the left hand, and the carriage is moved toward the stationary stop until the left marginal stop contacts the stationary stop. Then the Margin lever is depressed with the right hand and held in the depressed position while the operator moves the carriage toward the left or right until the desired writing position at which the marginal stop is to be active is set in registration with said center of the typing. When this position has been reached, both the Margin lever and the carriage release lever are released. The release of the carriage release lever re-engages the carriage with the escapement mechanism, and the release of the Margin lever allows the marginal stop to relock in the set position on the marginal rack, and thus the left marginal stop is reset to the desired position.

In order to set the right-hand marginal stop, the same carriage release lever and the same Margin lever are operated as described above. However, in this case the operator moves the carriage toward the left to bring the right marginal stop in contact with the stationary stop, and, as soon as said stationary stop is reached, the Margin lever is depressed and then the carriage is moved toward the right or left until the writing position at which the right marginal stop

is to be active is in registration with said center of the typing. As soon as this position is reached, both the Margin lever and the carriage release lever are released, thereby re-engaging the right marginal stop with the marginal rack and re-engaging the carriage with the escapement mechanism.

Referring to the drawings, which are merely given by way of example to illustrate the invention:

Figure 1 is a plan view of a portion of a carriage showing the preferred form of the invention, which includes a marginal rack and carrying my new marginal stops, my Margin lever and its associated longitudinal rod, my improved controlling governor, and other features of the invention, which will be hereinafter described in detail;

Figure 2 is a front elevational view taken along the lines 2—2 of Figure 1 and showing details of my new and improved marginal stops;

Figure 3 is a front elevational view taken along the lines 3—3 of Figure 1 and showing my controlling governor;

Figure 3a is a right end view of the mechanism shown in Figure 3, the end plate of the carriage having been omitted for the sake of clarity;

Figure 4 is an elevation similar to Figure 3, with the exception that the rod controlled by the Margin lever has, in an infinitesimal portion of an operating cycle, moved into contact with the rack;

Figure 4a is similar to Figure 3a, except that the positions of some of the elements have changed slightly;

Figure 5 is an elevational view similar to Figures 3 and 4, with the exception that the rod has moved downwardly to a point where the dog is brought into contact with the controlling governor and is arrested thereby;

Figure 5a is an end view similar to Figure 3a, showing endwise the new relation of the parts of Figure 5;

Figure 6 is an elevational view similar to Figure 5, with the exception that the carriage has been moved toward the left to a point where a tripping leg or stud on the marginal stop has engaged and displaced the controlling governor, thereby allowing the dog to move downwardly so that it may enter the slot formed in the marginal stop and thereby disengage its rack-engaging member from the rack;

Figure 6a is an end view showing the new relation of the parts depicted in Figure 6;

Figure 7 is a view similar to Figure 6, except that the dog has entered the slot in the marginal stop and is in engagement with a stud on the rack engaging member, so that further downward movement of the dog will disengage the member from the teeth of the rack. Figure 7 also shows a tripping member on the marginal stop as having engaged and displaced a member connected to the "margin release" key of the typewriter;

Figure 7a is an end view showing the relation of the elements depicted in Figure 7;

Figure 8 is a view similar to Figure 7, except that the rod and the dog have moved further downwardly, thereby disengaging the rack engaging member from the teeth of the rack, thereby making it possible to move the carriage to a desired position while the marginal stop is maintained stationary in respect to the counterstop;

Figure 8a is an end view showing the position relation of the elements as depicted in Figure 8;

Figure 9 is a view similar to Figure 8, with the

exception that the dog is against the left edge of the slot in the marginal stop as the carriage is moved toward the right;

Figure 10 is a perspective view of my new and improved right-hand marginal stop;

Figure 11 is an elevational view of the margin rack engaging member;

Figure 12 is a plan view showing the wedge-shaped portion of the member of Figure 11 entering the tooth of the marginal stop rack;

Figure 13 is a plan view of the modified form of the invention;

Figure 14 is an elevational view taken along the lines 14—14 of Figure 13;

Figure 15 is an end view with the end plate of the carriage omitted, showing the relation of the elements depicted in Figure 14; and

Figure 16 is a fragmentary view showing the marginal stop at rest against the stationary stop, and the dog entered into the slot in the marginal stop for disengaging the pivoted member therein from the teeth of the marginal stop rack and for holding said marginal stop immobile as the carriage is subsequently moved.

Referring now to Figures 1 and 2, the carriage of a typewriter or the like is designated generally by the numeral 20 and has a right end 21 and a left end 22. The carriage 20 is linearly movable on a frame in a conventional manner, fractions of said frame being designated by the numeral 29. A carriage release lever 23 is preferably positioned on the left end of the carriage and it is journalled thereon on a stud 24. This lever is connected to a conventional mechanism for disengaging the carriage from the escapement mechanism, so that when the lever is depressed the carriage is free to move in either direction. Since such arrangements are old in the prior art, it is not necessary to show details of the same herein. However, an example of one prior arrangement is that the escapement dog is disengaged from the escapement wheel, and another prior art arrangement disengages the feed rack from the feed pinion. On the right end 21 is mounted a stud 25, upon which is journalled a margin setting control or lever 26, upon which is imprinted the word "Margin."

Spring means 27, which may best be seen in Figure 3a, has one end thereof connected to a pin 28, which projects from the end of the lever 26, and the other end of this spring is connected to an extension 29a of the frame of the carriage. This spring urges the lever 26 upwardly, as seen in Figure 1, which is in a clockwise direction, as viewed in Figure 3a. A stop pin 30 is mounted on the extension 29a in a position to limit the upward movement of the lever 26.

The margin setting control or lever 26 has a depending arm 31, which when said lever is operated is adapted to act on the aforesaid conventional mechanism for releasing the carriage from the escapement mechanism. This depending arm is shown in the drawing as broken away, but it will be understood that it is operatively connected to the mechanism for disengaging the carriage from the escapement mechanism. It will also be understood that the action of the carriage release lever 23 and the action of the depending arm 31 on the "Margin" lever 26 are independent of one another. For example, the depressing of the lever 23 on the left end of the carriage is used for releasing the carriage in the ordinary manner, while the depression of the Margin lever 26 releases the carriage from the escapement mechanism as an integral part of the operation of

setting or resetting the marginal stop or stops. This lever also has a depending arm 32, which carries on its lower end a boss 33, which has a hole formed therein parallel to the axis of the stud 25. A rod 34 has a portion 35 of reduced diameter, which is pressed into the hole formed in the boss 33, or secured thereto in any other suitable manner. The left carriage end 22 carries a stud 36, upon which is journalled a boss 37, which is formed integral with a lever 38. The lever 38 carries on its forward end a boss 39, which has a hole formed therein and into which is pressed the left end portion 40 of the rod 34. This end portion 40 is preferably the same diameter as the right end portion 35. The right end 21 of the carriage has an open clearance slot 41 formed therein to accommodate the rod 34. Likewise, the left end 22 of the carriage has a like clearance slot 42 formed therein.

It will be noted that in Figure 1 and other figures the front portions of the carriage ends 21 and 22 are broken away. However, it will be understood that the platen is supported by said broken-away portions of the carriage ends, and that for the sake of clarity the platen is omitted from the drawing.

A marginal rack 43 is supported by the end members 21 and 22 and may be secured thereon in any suitable manner, for example, by means of screws 44. The marginal rack has a series of teeth 45 formed therein, which are engaged by members carried by the marginal stops, and which will be presently described.

My new and improved marginal stops are substantially identical, except that they are "rights" and "lefts." The right-hand marginal stop is designated generally by the numeral 46 and the left-hand marginal stop is designated as 46a. The marginal stop 46 includes a body portion, which may best be seen in Figure 10. It is generally U-shaped in cross section, having a horizontal bottom portion 47 with spaced parallel sides 48 and 49. The body portion has a lateral slot 50 formed therein, dividing the side 48 into vertical portions 51 and 52 and the side 49 into vertical portions 53 and 54. Secured between the vertical portions 51 and 53, in spaced relation to the bottom 47, is a block 55, and in alignment therewith, between the vertical portions 52 and 54, is a second block 56. These blocks have aligned holes formed therein to accommodate a bearing pin 57. The vertical portion 53 has intermediate the ends thereof a laterally extending tab 58, which forms a stop, the function of which will presently be described. The vertical portion 54 has secured thereto a stud 59, which is adapted to displace my controlling governor, which will also be presently described. The upper end of the vertical portion 54 has a bevel 60 formed therein, the function of which is to guide the dog 105 into the slot 50 in a manner which will presently be described.

A marginal stop locking member, generally designated by the numeral 61 and hereinabove referred to as the inner member, has a body portion 62, a vertical extension 63 of which carries a stud 64. The body 62 has a bearing hole 65 formed therein parallel to and spaced apart from the stud 64. By provision of this bearing hole the locking member 64 is journalled on the pin 57, the latter being mounted in the aligned holes formed in the blocks 55 and 56. Extending downwardly from the body portion 62 is a tooth engaging member 66. This tooth engaging member, as may be best seen in Figure 12, has a generally

rectangular body portion 67, which has formed integral therewith an apex portion 68 having sides which are angular to facilitate its entering into the space between any two teeth formed on the rack 43. A spring 69 (Figure 1) has one end thereof secured to the extension 63, and the other end is secured to the vertical portion 53, wherefore the tooth engaging member is normally positioned into marginal stop holding position. When the stud 64 is depressed by a dog member to be presently described, the marginal stop locking member 61 is swung transversely of the rack 43 against the urge of said spring 69 about the pin 57 as an axis, in a counterclockwise direction as viewed in Figure 8, and thereby the tooth engaging member 66 is disengaged from the teeth of the rack 43. The body portion 62 has a downwardly extending tab 70, which is in vertical alignment with the side 48 of the marginal stop. The tab 70 carries a stud 71, upon which is journaled a pawl lever 72.

A spring 73 has one end secured to the tab 70 and the other end secured to the pawl 72, so that the spring urges the pawl in a counter-clockwise direction, as viewed in Figure 2. A stop pin 74 is carried by the tab 70 and is so positioned thereon that the pawl 72 is normally held in position against rightward swinging displacement. The pawl 72 has a beveled face 75. The left edge of this pawl terminates in the rounded knob or lobe 76. The functions of both the beveled edge and the knob will presently be described. The U-shaped channel defined by the sides 48 and 49 and the bottom portion 47 forms a working fit with the marginal rack 43, so that the marginal stop may be easily moved along the rack after the member 66 is disengaged from the teeth of the rack. Mounted in the marginal stop, between the vertical portions 52 and 54 and forming a working fit with the surface of the marginal rack 43, is a block member 77, which is secured therein in any suitable manner, for example, by means of pins 78.

The frame 29 of the typewriter, see Figures 2, 3, etc., has an opening 109 formed therein. Projecting through this opening and extending into the path of movement of the pawl 72 of the marginal stop 46 is a counterstop member 79, which is operatively connected in a manner not shown to a conventional margin release key of the typewriter. Said counterstop is engageable by each of the marginal stops 46, 46a in the position each such stop defines. Since margin release arrangements are old in the art and do not form a part of the present invention, it is not deemed necessary to show the details thereof. However, it will be understood that the normal position of the counterstop 79 is shown in Figures 2 and 3. Lightly active spring means, not shown, normally urge the stop 79 against the right edge of the opening 109 in the frame 29.

When the carriage is moving to the left, which is the normal movement as the typing progresses, the lobe 76 on the pawl 72 engages the counterstop 79 and moves it, against the urge of its spring, into contact with the surface 111 of the opening 109. This means that when the end of a line of typing is reached, the lobe 76 of the pawl displaces the counterstop 79 to the left, and by well-known means the motion so given the counterstop causes operation of a usual line-end lock mechanism. Normally, the counterstop 79, as stated above, has its right edge in contact with the surface 110 of the opening 109, and the left

edge of the counterstop is in alignment with the center of the typing.

When the end of a line of typing is reached and the lobe 76 displaces the stop 79, as described above, and then it is desired to add several additional letters to the line being typed, the operator merely depresses the margin release key on the typewriter and thereby withdraws the counterstop 79 sufficiently downward to clear the lobe 76. As this is done, the counterstop springs to the right, so that its right edge is in contact with the surface 110. Therefore, when then the margin release key is released by the operator, the counterstop 79 moves upwardly to its normal position, and in so doing it engages and moves upwardly along the beveled face 75 of the pawl, displacing the latter idly leftwardly against the urge of the spring 73, so that the stop becomes positioned to the right of the pawl 72 and additional typing may then be effected. When thereupon the carriage is returned to begin a new line of typing, the beveled surface 75 engages the stop 79, and the pawl 72 swingably yields in a clockwise direction about its pivot 71. As soon as the pawl 72 passes the stop 79, it returns to its normal position against the stop pin 74 under the urge of the spring 73. This pawl arrangement is not new in typewriters and does not form part of the invention. It is merely described to show the flexibility of my new and improved marginal stops. The left-hand marginal stop 46a is comprised of elements which substantially correspond to those described in connection with the right-hand marginal stop 46, with the exception of the arrangement of the tab 70. Elements of the left-hand marginal stop 46a are designated by the same numerals as the corresponding elements of the right-hand marginal stop, except that they are each followed by the exponent letter "a." As to the tab 70 on the marginal stop 46, which carries the movable element 72, there is a substantially corresponding tab rigid on the left marginal stop 46a which is designated by the numeral 112. This tab is generally rectangular in form and has in the lower right-hand corner thereof a lobe 113, which limitedly engages the counterstop 79 when the carriage is returned to begin a new line of typing.

Pivotedly mounted on the frame of the typewriter and substantially laterally coincident with the counterstop 79 is an element 80, which is termed "controlling governor." The governor 80 is journaled on a stud 81, which is carried on the frame 29 of the typewriter. This governor is generally rectangular in form and has its upper end 82 angular, as shown in Figure 5a, so that it is parallel to the lower surface of the dog 105 as the latter is swung downwardly into engagement therewith. The governor 80 has fast thereon two rearwardly projecting pins 83 and 84, which are parallel to each other and which are spaced apart sufficiently for a spring 85 in the form of a flexible finger to have a working fit between them. The spring 85 has its lower end fixedly secured on the frame 29 and the function of this spring is to constantly urge the governor 80 to a position where its longitudinal axis is vertical.

A bracket member 86 is mounted on the frame 29 of the typewriter, and, as seen in Figure 3a, it is secured to the frame 29 by a horizontal portion 87 and has a vertical portion 88 branching out in an upper U-shaped portion 89 which, as may be seen in Figure 1, has spaced parallel sides 90 and 91. The vertical portion 88 has between

the base 87 and the U-shaped portion 86 a projecting ear 92, which carries a stud 93. A shaft 94 is mounted in aligned holes formed in the sides 90 and 91 of the U-shaped channel 86 and journalled on this shaft are the two legs 96 and 97 of a yoke member 98. The yoke member 98, as may best be seen in Figure 3a, is threadedly engaged by a long shouldered screw 99, which has journalled thereon, between its head 100 and the yoke member 98, a sleeve 101, and abutting the end of the yoke member 98 is a free washer 102, so that the sleeve 101 and the washer 102 are freely rotatable.

This assembly is herein termed a "dog" and is hereinafter designated generally by the numeral 105. The U-shaped portion 86 has a stop pin 103 positioned in aligned holes therein for limiting the downward movement of the dog 105, and a second stop pin 104 is positioned in other aligned holes in the sides 90 and 91 for limiting the extreme upward movement of the dog 105.

The yoke member 98 has a cross-pin 106, and a spring 107 has one end secured to the pin 106, and the other end is secured to the stud 93 carried in the ear 92, so that it constantly urges the dog 105 upwardly and into contact with the stop pin 104.

The normal relation of the dog 105 with respect to the upper end 82 of the governor 80 is such that a clearance 108 is provided, as can be seen in Figures 3 and 3a. This clearance allows the square edges of the upper surface 82 of the governor 80 to clear the dog 105 as the governor swings on its axis 81 to its normal position. When the governor is displaced by the tripping leg 59, the square corners have a function which will presently be described.

Referring to Figure 1, it will be noted that the tripping legs or studs 59 and 59a carried by the right and left-hand marginal stops project forwardly beyond the main body of my controlling governor 80, so that when the carriage is moved to the left far enough for the leg 59 to engage the governor 80, the latter will be displaced swingably in a counter-clockwise direction about the pivot 81, as shown in Figures 6 to 9, inclusive. Similarly if the carriage is moved far enough to the right, the governor 80 will be engaged by the tripping leg 59a and will be displaced swingably in the opposite direction (clockwise) about the pivot 81. Normally, the governor 80 stands upright beneath the dog 105, spaced therefrom by a slight vertical clearance 108 and thus limits the movement of the dog 105 downwardly to the amount of the clearance 108. This means that the movement of the dog 105 downwardly is arrested by the governor 80 unless one or the other of the marginal stops 46, 46a is stationed in or moved to a position wherein the governor 80 is displaced by one of the tripping legs 59, laterally to one or the other side from vertical position, thereby allowing the dog 105 to move downwardly unobstructed, so that it can perform functions which will presently be described.

Operation

First, the operation will be described in connection with resetting the right-hand marginal stop 46 to a new desired location. Now, in order to have a better understanding of the following description in connection with Figures 3 to 9, inclusive, all of these figures include a reference line which is designated by the numeral 114, so that as the description of these figures progresses the 75

movement of the carriage toward and away from this reference line may be readily seen.

Supposing it is desired to reset the right-hand marginal stop 46, Figure 3, to a new location, and assuming also that the position of the carriage is such that the marginal stop 46 is away from the counterstop 79. The first step is to depress the Margin lever or setting control 26 on the right end of the carriage as far as it will go. In the partial downward movement of the Margin lever 26 thus effected, the rod 34 moves to a position such as is illustrated in Figures 4 and 4a, where it contacts the dog 105. During this partial downward movement which is always possible, the arm 31 actuates the conventional mechanism for releasing the carriage from the control of the letter-feed escapement. During the next increment of movement of the rod 34 downwardly, the dog 105 encounters the upper end 82 of the controlling governor 80 and is arrested thereby. The carriage having been released for movement, the operator then, while still exerting pressure on the lever 26, moves the carriage toward the left, thereby bringing the tripping leg 59 on the right marginal stop nearer and nearer to the governor 80. As this movement progresses, the leg 59 on the marginal stop 46 engages and displaces the governor 80 by swinging it in a counter-clockwise direction, as viewed in Figure 6, so that the dog 105 consequently, due to the pressure still exerted on the lever 26, will move downwardly further, and will contact upon the upper end of the portion 54 of the right-hand marginal stop (the position shown in Figures 6 and 6a). As this takes place the stop pawl 72 has not yet come into contact with the counterstop 79. However, the operator continues to move the carriage to the left until as shown in Figure 7 the lobe 76 of the pawl 72 has engaged the counterstop 79 and has moved it to a position where its left face is in contact with the surface 111 of the opening 109 in the frame 29. Meanwhile the controlling governor 80 has been displaced still further to the left, and the dog 105 because of the continued operating force applied on the lever 26 has moved down the incline 60 on the right marginal stop and has thereby been guided into the open slot 58 to a position in contact with the stud 64 on the marginal stop locking member 61.

During the above-described movement, when the tripping leg 59 engages the governor 80 to shift it from the position shown in Figure 5 to the position shown in Figure 6, the upper right-hand corner of the governor 80 moves the rod 34 upwardly (due to the fact that the upper end 82 of the governor 80 has square edges instead of rounded edges), and this provides momentarily a resistance in the movement of the carriage. On the other hand, when the rod 34, after having been shifted upwardly via the right-hand square corner on the upper end of the governor 80, suddenly drops down on to the top flat edge of the comparatively wide vertical portion 54 of the marginal stop, the position shown in Figure 6, with a perceptible shock which can be felt by the operator through the finger or thumb which is depressing the Margin lever 26, this shock is a perceptible indication to the operator to decelerate the speed at which the carriage is being moved, as the marginal stop to be set is by that time approaching the stationary stop.

The magnitude of this shock depends upon the width of the governor and the drop of the rod 34. By the width of the governor is meant the linear dimension of the square edge 82. By the drop

of the rod 34 is meant the distance it moves downwardly after it leaves the right-hand corner of the upper edge of the governor and arrives on the surface of the vertical portion 54 of the marginal stop, as may clearly be seen in Figures 5a and 6a. The magnitude of the zone in which deceleration may be effected depends on the width of the portion 54 of the marginal stop, as viewed in Figure 2. The greater this width, the greater the magnitude of said zone. In Figure 2 it will be noted that the wide portions 54 and 54a are opposite each other to decelerate for right and left-hand marginal settings, respectively.

As the slot 50 of the marginal stop registers with the dog 105 and the operator continues to exert pressure downwardly on the Margin lever 26, the dog 105 acts vertically against the stud 64 in the marginal stop locking member 61 and causes the latter to swing in respect to Figure 8a in a counter-clockwise direction about its axis 57, thereby disengaging the tooth-engaging member 66 on its lower end from the teeth 45 of the marginal rack 43. This is the position shown in Figures 8 and 8a. It will thus be seen that the governor 80 and the portion 54 on said marginal stop constitute in association with the dog 105, a means to suppress stop releasing operation of the control 26 until the carriage is stationed in or is moved to the position which the marginal stop defines. After the marginal stop has become released, the operator, while still keeping the lever 26 depressed, moves the carriage to the right or the left until the carriage is in the position where it is desired to have the lines of typing terminate. From Figure 9, wherein the carriage is shown moved leftwardly, it will be noted that, as the operator starts this movement of the carriage, the dog 105 is contacted by the left edge of the slot 50 formed in the marginal stop and thereby the latter is held stationary. If the carriage is moved leftwardly the dog 105 is contacted by the right edge of the slot 50. When the desired point is reached, the operator releases the Margin lever 26 and the following events occur: The setting control 26 with its associated bar 34 returns to the normal position seen in Figures 3 and 3a. In the first part of such return the dog 105 swings about its axis in a counter-clockwise direction, due to the urge of the spring 107. The marginal stop locking member 61, under the urge of the spring 69, is moved in a clockwise direction until it comes to rest against the stop tab 58, by which time the tooth-engaging member 66 has entered into the space between the two nearest adjacent teeth of the rack 43. Consequently the right marginal stop 46 has become moved to reset and locked in the new desired position. The restoring movement of the Margin lever 26 continues after the dog 105 has reached normal position, and in such continued movement the carriage becomes restored to the control of the carriage feed mechanism.

It will be understood that the sequence of events described above occur in very rapid succession and without any real pauses therebetween. The pauses given in the course of the description are merely to break the sequence up into steps, so that a better understanding of the entire operation may be had. In actual practice, the whole operation is effected in a matter of a second or less. In the several figures illustrating the above-described movements, the relative distance between the reference line 114 and the end 21 of the carriage may be readily followed.

Now to set the left-hand marginal stop 46a, 75 the Margin lever, move the carriage for the mar-

the steps employed are exactly the same as described above for setting the right-hand marginal stop 46, except in reference to the direction of motion of the carriage required to bring the stop 46a into contact with the counterstop 79. For example, if it were desired to set the left marginal stop 46a with the position of the carriage prevalent as in Figure 2, the operator would apply pressure on the Margin lever 26. This causes the rod 34 to move downwardly into contact with the dog 105, and during this time the arm 31 on the Margin lever 26 actuates the mechanism for disengaging the carriage from the escapement mechanism. Then during the next increment of movement, the clearance space 108 between the dog 105 and the upper end 82 of the governor 80 is taken up so that the dog comes to rest on the governor end 82. Upon being freed the carriage is moved to the right until the tripping leg 59a on the marginal stop 46a engages the governor 80 and causes it to swing about its axis 81 in a clockwise direction. As soon as the upper end 82 of the governor 80 is moved from under the dog 105, the rod 34 will resume its downward movement due to the fact that the operator continues to press the Margin lever downwardly. The left marginal stop is by this time in an approximate position below the dog 105, the latter of which then moves further downward and contacts the pivotal surface 60a on the left marginal stop. As the marginal stop reaches a position in which its lobe engages the counterstop 79, the dog is guided into the open vertical slot 50a of the marginal stop 46a and into contact with the stud 64a of the marginal stop locking member 61a. Further movement downwardly of the rod 34, effected under sustenance of operating pressure on the Margin lever 26, causes the locking member 61a to swing about its axis 57a in a direction to disengage the tooth-engaging portion 66a from the teeth of the marginal rack. While this is occurring, the lobe 113 is in contact with the counterstop 79, generally in alignment with the center of the typing. 45 As soon as the locking member 61a is disengaged from the rack, the operator moves the carriage toward the left or to the right until the point is reached where it is desired to have the left marginal stop active in the future. The operator then releases the Margin lever 26, allowing the locking member 61a to re-engage the teeth of the marginal rack, and, at the same time, all of the elements involved in the operation return to their normal positions. 50 Obviously, if the marginal stop which requires adjustment happens to be in a position against the counterstop 79 when it is decided to effect its adjustment, then the Margin lever 26 is operable to its full extent without interruption, this resulting in the immediate release of the margin stop from the rack, and in its temporary localization in respect to the frame. Obviously, the full movement of the lever 26 will make the operator conscious of the fact that adjustment of the margin stop will then immediately ensue if the carriage is merely moved to the position where the marginal stop is desired to be active, the marginal stop becoming fixed in adjusted position upon release of the lever 26. 55 From the above description it will be seen that my new and improved mechanism operates in a manner requiring a minimum of attention and concentration by the operator, as all the operator has to do is to apply operating pressure on the Margin lever, move the carriage for the mar-

ginal stop to be reset to become located against the counterstop 79, and then move the carriage in the appropriate direction to the point where the marginal stop is to be active in the future, the setting operation being concluded by the operator releasing the Margin lever 26. No separate and sequential operations of different controls are necessary. The operator does not have to remember any difficult and varied procedure and the setting operation is effected almost as rapidly as is the returning of the carriage to begin a new line of typing.

The modified form of my invention

Referring now to Figures 13 to 16, inclusive, I show a modified form of the invention, in which the setting procedure requires more manipulative steps. In these figures the same elements shown in Figures 1 to 12 are employed, with the exception that the controlling governor 80 and the tripping legs 59 and 59a on the marginal stops for actuating the same are omitted. The same numerals used on the elements of Figures 1 to 12 are applied to corresponding elements employed in Figures 13 to 16, inclusive.

Operation of the modified form of the invention

First, the operation will be described in connection with resetting the right-hand marginal stop 46 to a new desired location. The first step is to depress the carriage release lever 23 on the left end of the carriage. This releases the carriage from the escapement mechanism, so that the carriage may be moved. While the lever is held operated, the operator moves the carriage toward the left until the right marginal stop contacts and moves the counterstop 79 on the frame into contact with the left side edge 111 of the opening 109 in the frame 29. The operator then, additionally to the carriage release lever 23, depresses the Margin lever 26, thereby moving the rod 34 downwardly against the dog 105 and thereby causing the latter to move downwardly into the slot 50 against the urge of the spring 107. This is the position shown in Figure 16.

As the operator continues to exert pressure on the Margin lever 26, the dog 105, acting against the stud 64, causes the marginal stop locking member 61 to swing in a counter-clockwise direction, as viewed in Figure 15, thereby disengaging the tooth-engaging member 66 on the lower end of the locking member from the teeth 45 of the marginal rack 43. Then the operator, while still continuing to exert pressure on the Margin lever 26 and the carriage release lever 23, with the right and the left hand respectively, moves the carriage toward the right or to the left until the carriage is in the new position at which the right marginal stop is to be active. As soon as this point is reached, the operator then releases both the carriage release lever 23 and the Margin lever 26, thereby causing the locking of the right-hand marginal stop in the desired position and the restoration of the carriage to the control of the letter feed mechanism.

The locking of the stop is effected in the following manner: As soon as the Margin lever 26 is released, it and the rod 34 are moved upwardly under the urge of the spring 27. As the rod 34 starts moving upwardly, the dog 105 also moves upwardly under the urge of the spring 107 until it is arrested by the stop 104. Now, as the dog 105 moves upwardly out of the slot 50, the stud 64 on the marginal stop locking member 61 moves upwardly under the urge of the spring 69

until the tooth-engaging member 66 on the lower end of the member 61 enters between two adjacent teeth of the marginal rack 43, and finally said locking member is arrested by the tab 58 on the marginal stop and overhanging the slot 50.

If it is desired to reset the left marginal stop to a new position, the operation is similar to that described above, except for the direction of movement of the carriage. For example, the operator depresses the carriage release lever 23 with the left hand and moves the carriage toward the right until the left-hand marginal stop comes to rest against the counterstop 79 on the frame of the typewriter. When the left marginal stop is in this position, its slot 58a is beneath the dog 105. The operator then depresses the Margin lever 26, thereby moving the rod 34 downwardly. The rod 34 in turn moves the dog 105 downwardly into the slot 58a in the left marginal stop and this disengages the marginal stop locking member 61a from the marginal rack and at the same time renders the marginal stop stationary. Then the operator, while still holding both the carriage release lever 23 operates also the Margin lever 26 and moves the carriage toward the left or the right until the point at which the left marginal stop is to be set is in line with the center of the typing. Then the operator releases both levers, thereby re-engaging the carriage with the escapement mechanism and locking the left marginal stop in the desired new position.

Obviously, in the event the marginal stop to be set is not fully in carriage-movement-limiting engagement with the counterstop 79 when the operator applies operating pressure on the lever 26, then the dog 105 will be blocked against effective operation inasmuch as it clashes against the top level 60 of the marginal stop. This will compel the operator to move the carriage to locate the marginal stop against the counterstop if the lever 26 is to be operative for marginal stop releasing function.

It is to be understood that the above detailed description of the present invention is intended to disclose an embodiment thereof to those skilled in the art, but that the invention is not to be construed as limited in its application to the details of construction and arrangement of parts illustrated in the accompanying drawings, since the invention is capable of being practiced and carried out in various ways without departing from the spirit of the invention. The language used in the specification relating to the operation and function of the elements of the invention is employed for purposes of description and not of limitation, and it is not intended to limit the scope of the following claims beyond the requirements of the prior art.

What is claimed is:

1. In a typing machine having a frame, a carriage movable thereon, escapement mechanism for controlling the movement of said carriage thereon in one direction, a marginal rack carried on said carriage and settable marginal stops on said rack, a stationary stop on said machine, locking means on each marginal stop urged into locking engagement with said rack, dog means on said machine for disengaging the locking means of either one or the other of said marginal stops and holding the latter stationary as the carriage is subsequently moved, a margin-setting lever means on said carriage adapted, when actuated, to release the carriage from said escapement mechanism and then to actuate said dog means, and arresting means on said machine in the path of

movement of said marginal stops for holding said lever means immobile after said carriage has been released, said arresting means being adapted to be displaced by either one of said marginal stops as the latter approaches said stationary stop by the movement imparted to the carriage by an operator, thereby enabling said lever means to actuate said dog means.

2. In a typewriting machine having a carriage movable lineally on a frame and having a releasable carriage feed mechanism, the combination of a marginal rack mounted on said carriage, a marginal stop carried on said rack, locking means on said marginal stop normally engaging the teeth of said rack, a lever on said carriage adapted to be actuated by an operator for resetting said marginal stop, means controlled by said lever adapted in the initial phase of its movement to release said carriage feed mechanism, a stationary stop on said frame in alignment with the center of the typing, a dog operatively supported on said frame for engaging said locking means and unlocking said marginal stop and holding it against movement when the carriage is subsequently moved to reset the same, means moved by said margin-setting lever for operating said dog, and a controlling governor on said frame adapted to arrest said last means after said initial phase of movement of said lever, said governor being disposed in the path of movement of said marginal stop and displaced thereby as the operator moves the carriage to bring said marginal stop into engagement with said stationary stop, thereby freeing said last means to operate said dog for the latter to perform its aforesaid function as said lever completes its movement.

3. In a typewriting machine having a carriage movable lineally on a frame and having a releasable carriage feed mechanism, the combination of a stop member on said frame, a marginal rack mounted on said carriage, a marginal stop carried on said rack, a locking member on said marginal stop constantly urged into locking relation with the teeth of said rack, guide means formed on said marginal stop extending toward said locking member, a margin-setting lever on said carriage adapted to release said carriage feed mechanism during an initial portion of the movement of said lever, an actuating rod also moved by said lever, a dog on said frame adapted subsequently to said initial portion of movement of said lever to be actuated by said rod for disengaging said locking means from said rack, and a governor on said frame for arresting said dog after said carriage is released, said governor being disposed in the path of and adapted to be displaced by said marginal stop as the latter approaches the stop member on the frame, whereby said dog is freed to be moved downwardly by said rod and is guided into engagement with said locking member by said guide means.

4. In a typewriter in combination, a frame, an escapement mechanism, a carriage slidably mounted on said frame and operatively connected to said escapement mechanism, a marginal rack carried by said carriage, right and left hand settable marginal stops, each carrying a pivoted member engaging said rack and a tripping leg; and a combined marginal stop releasing, holding, and resetting mechanism comprising a universal dog, a driving unit, and a controlling element mounted respectively at a fixed position on said frame, on the carriage and at another fixed position on said frame; said driving unit, when force is applied thereto, to reset said right marginal

stop, being adapted to release said carriage from said escapement mechanism, enabling the same to slide toward the left near the limit of its stroke, thereby, by means of the tripping leg of said marginal stop, actuating said controlling element and enabling said dog to free said member of said marginal stop from said rack and to hold said stop stationary as said carriage is moved toward the right up to the position at which said stop is to be reset, said driving unit, when said force is removed therefrom, enabling said carriage to re-engage with said escapement mechanism and at the same time releasing said dog and enabling said member of said marginal stop to re-engage a tooth of said rack which is in registration with said dog.

5. In a typewriter in combination, a frame, an escapement mechanism mounted on said frame, a carriage engaging said mechanism, a lever for disengaging said carriage from said mechanism, a plurality of marginal stops slidably mounted on said carriage, a dog for resetting either of said marginal stops along said carriage, a driving unit adapted to impart power first to said lever for disengaging the carriage from said mechanism and then to impart power to said dog, and a controlling element on said frame in the path of and displaceable by said stops and normally preventing the delivery of power to said dog for actuating the same, said element being adapted to be displaced by either one of said stops to effect the actuation of said dog by said power.

6. In a self-adjusting margin device, a frame, a carriage, a marginal rack mounted on said carriage, a plurality of settable marginal stops on said rack, escapement mechanism operatively connected to said carriage, means for releasing said carriage from said escapement mechanism, dog means on said frame for releasing either one of said marginal stops from said rack, said dog means being adapted to hold either one of said stops in a predetermined position with respect to a point on said frame, governing means actuated by the impact thereagainst of the stop to be set for rendering said dog means effective, means for re-engaging said stops on said rack, means for re-engaging said carriage with said escapement mechanism, and a driving unit to cause each of said means to operate successively.

7. In a typewriter, a frame, a stationary stop thereon, a carriage, marginal stops thereon, manually operable means to be actuated by an operator during at least a portion of a marginal stop resetting operation, and means to impart to an operator a perceptible indication, via said manually operable means, as the operator is moving said carriage, that the marginal stop to be reset is near the stationary stop and the carriage should be decelerated.

8. In a typewriting machine having a carriage lineally movable on a frame and having a releasable carriage feed mechanism, the combination of two marginal stops, rack means extending in parallel to the carriage and along which said stops are individually adjustable, locking means carried on each stop and biased to engage said rack means for holding the said stops individually adjusted, counterstop means on the frame engageable by each stop in a position of the carriage which each stop defines, each said locking means including a part operable transversely of the rack means to unlock its related stop, dog means on said frame op-

erable transversely of the carriage to release the locking means of whichever stop is brought into a position of engagement with the counterstop means, a margin setting control on the carriage, rod means extending on the carriage lengthwise thereof and operable transversely of the carriage by said setting control to operate said dog means in any position of the carriage, means to suppress stop-releasing operation of said dog means by said setting control unless one or the other of said stops is in or reaches a position of engagement with said counterstop means, said setting control capable of some initial movement unrestricted by said suppressing means, means controlled by said initial movement of said setting control to release said carriage feed mechanism, and means to disable said suppressing means by movement of either of said stops into its position of engagement with the counterstop means, whereby after an initial impartation of movement to said setting control the carriage is freely movable to bring either stop into a relation of engagement with said counterstop means, and whereby a further movement can then be imparted to said setting control which will cause the rod means to impart a movement to the dog means which will release the locking means of the stop which is in said relation of engagement with the counterstop means.

9. In a typewriting machine having a carriage movable lineally on a frame and having a releasable carriage feed mechanism, the combination of a marginal stop, means to support said marginal stop for adjustment in a direction parallel with the movement of the carriage to define different marginal positions, means to lock the marginal stop in adjusted position and in condition for release, a marginal stop setting control, means always operable by said control to release said feed mechanism, means adapted to respond to said control to release said lock-means, and means associated with said lock releasing means and controlled by said marginal stop, to govern the former to respond effectively to said control only if the carriage is in the position which said marginal stop happens to define or upon movement of the carriage to such position.

10. In a typewriting machine having a carriage movable lineally on a frame and having a releasable carriage feed mechanism, the combination of a marginal stop, means to support said marginal stop for adjustment in a direction parallel with the movement of the carriage to define different marginal positions, means to lock the marginal stop in adjusted position and in condition for release, a marginal stop setting control, means always operable by said control to release said feed mechanism, means adapted to respond to said control to release said lock means, means associated with said lock releasing means and controlled by said marginal stop, to govern the former to respond effectively to said control only if the carriage is in the position which said marginal stop happens to define or upon movement of the carriage to such position, and a carriage release control carried on the carriage for releasing said feed mechanism without releasing said lock means.

11. In a typewriting machine having a carriage movable lineally on a frame and having a releasable carriage feed mechanism, the combination of a marginal stop, means to support said marginal stop for adjustment in parallel with the move-

ment of the carriage, means to lock the marginal stop in adjusted position and in condition for release, a counterstop with which said marginal stop assumes an engaged relation in limiting carriage travel in one direction, a manually operable control, means responsive always to said control to release the carriage feed mechanism of the machine, a device adapted to respond to said control to release the locking means for the marginal stop and additionally to render the marginal stop stationary with respect to the counterstop, and operation governing means for said device including means adjustable along with said marginal stop, to cause said device to respond to said control for effective action only in the event the marginal stop and said counterstop are in or approximate said engaged relation, or consequently to establishment of such relation through carriage movement under condition of operating force maintained on said control.

12. In a typewriting machine having a carriage movable lineally on a frame and having a releasable carriage feed mechanism, the combination of a marginal stop, means to support said marginal stop for adjustment in parallel with the direction of movement of the carriage to define different marginal positions, means to lock the marginal stop in adjusted position and in condition for release, a marginal stop setting control, means operable by manipulation of said control in one direction to release said locking means, marginal stop controlled governing means to control effective operation of said operable means by said control to ensue only if said carriage is in the position said marginal stop happens to define, or upon establishment of such position under condition of manipulative force applied on said control in said one direction, and other means operable by manipulation of said control in said one direction, independently of said governing means, to release said feed mechanism.

13. In a typewriting machine having a carriage movable lineally on a frame and having a releasable carriage feed mechanism, the combination of a marginal stop, means to support said marginal stop for adjustment in parallel with the direction of movement of the carriage, means to lock the marginal stop in adjusted position and in condition for release, a counterstop with which said marginal stop assumes an engaged relation in limiting carriage travel in one direction, a marginal stop setting control on the carriage, means operable by manipulation of said control in one direction to release said locking means, marginal stop controlled governing means to control effective operation of said operable means by said control to ensue only if said marginal stop and counterstop are in said engaged relation or upon establishment of said relation under condition of manipulative force applied on said control in said one direction, and other means operable by manipulation of said control in said one direction, independently of said governing means, to release said feed mechanism.

14. In a typewriting machine having a carriage movable lineally on a frame and having a releasable carriage feed mechanism, the combination of a marginal stop, means to support said marginal stop on the carriage for adjustment in parallel with the movement of the carriage, means to lock said marginal stop in different adjusted positions comprising a row of teeth on the carriage and a lock on the marginal stop normally in stop locking engagement with said teeth and releasable therefrom, a counterstop on the frame with which said

marginal stop assumes an engaged relation in limiting carriage travel in one direction, a marginal stop setting control on the carriage, dog means on the frame communicative with said marginal stop lock for releasing operation thereon when said marginal stop approximates said engaged relation with said counterstop, means adapted to operate said dog means by said control in any position of the carriage, means controlled by said marginal stop to govern operation of said dog means by said operating means to ensue only upon operating force on said control if the marginal stop approximates said position of engagement with said counterstop or following establishment of such position by carriage movement under condition of operating force applied on said control, and means readily responsive to said control independently of said governing means to release said carriage feed mechanism.

15. In a typewriting machine having a carriage member movable on a frame member and having a releasable feed mechanism for said carriage member, the combination of a marginal stop on one of said members adjustable in a direction parallel to the movement of the carriage member to define different margin positions, means to lock said marginal stop in said positions and in condition for release, a marginal stop setting control, means always operable by said control to release the said feed mechanism, means adapted to respond to said control to release said lock means, and means associated with said lock releasing means and controlled by said marginal stop to govern the former to respond effectively to said control only if the carriage member occupies substantially a position defined by said marginal stop, or upon establishment of such position, said governing means comprising marginal stop controlled means on the other one of said members to block effective operation of said lock releasing means in all positions of the carriage member except when the carriage member nears the marginal position defined by said stop, and comprising also surface means on the marginal stop cooperative with said lock releasing means to block it thereafter until the carriage member reaches substantially the exact position which the marginal stop defines.

16. In a typewriting machine having a carriage member movable on a frame member and having a releasable feed mechanism for said carriage member, the combination of a marginal stop on one of said members adjustable in a direction parallel to the movement of the carriage member to define different margin positions, means to lock said marginal stop in said positions and in condition for release, a marginal stop setting control, means adapted to respond to said control to release said lock means, and means associated with said lock releasing means and controlled by said marginal stop to govern the former to respond effectively to said control only if the carriage member occupies substantially a position defined by said marginal stop, or upon establishment of such position, said governing means comprising marginal stop controlled means on the other one of said members to block effective operation of said lock releasing means in all positions of the carriage member except when the carriage member nears the marginal position defined by said stop, and comprising also surface means on the marginal stop to block said lock releasing means against operation until the carriage member is moved substantially to the exact position which the marginal stop defines.

17. In a typewriting machine, having a carriage member movable linearly on a frame member and having a releasable feed mechanism for the carriage member, the combination of a marginal stop, means to support said marginal stop for adjustment on one of said members in parallel with the direction of carriage movement, means to lock said marginal stop in different margin defining positions of adjustment on its supporting member including a row of teeth on said member and a locking member on said marginal stop releasable from said teeth, an element on the other one of said members operable transversely of said carriage member to release the locking member of the marginal stop, a governor for said element supported on the said other member for swinging movement in the direction of carriage movement from a position blocking margin stop releasing operation of said element to a position freeing it for operation, and means on said marginal stop to swing said governor to a position freeing said element for operation as the carriage member is moved to the position the said marginal stop defines.

18. In a typewriting machine having a carriage movable linearly on a frame and having a releasable carriage feed mechanism, the combination with a marginal stop on the carriage, means to support said marginal stop on the carriage for adjustment parallel to the direction of movement thereof, means to lock the marginal stop on the carriage in adjusted position and in condition for release, a counterstop on the frame with which said marginal stop assumes an engaged relation in limiting carriage travel in one direction, a marginal stop setting lever on the carriage having an initial phase of movement to effect the release of the carriage feed mechanism, means operable by said lever in a further phase of movement thereof to unlock the marginal stop from adjusted position on the carriage and to render it stationary with respect to the counterstop, and means including governor means supported on the frame and controlled by the marginal stop to block stop-unlocking operation of said operable means by said lever unless the marginal stop is in or approximates engaged relation with said counterstop or until the marginal stop is brought into said engaged relation.

19. In a typewriting machine having a carriage movable linearly on a frame and having a releasable carriage feed mechanism, the combination of a marginal stop, means to support said marginal stop for adjustment in parallel with the movement of the carriage, means to lock the marginal stop in adjusted position and in condition for release, a counterstop with which said marginal stop assumes an engaged relation in limiting carriage travel in one direction, a manually operable control, means responsive always to said control to release the carriage feed mechanism of the machine, a device adapted to respond to said control to release the locking means for the marginal stop and additionally to render the marginal stop stationary with respect to the counterstop, operation governing means for said device including means adjustable along with said marginal stop, to cause said device to respond to said control for effective action only in the event the marginal stop and said counterstop are in or approximate said engaged relation, or consequently to establishment of such relation through carriage movement under condition of operating force maintained on said con-

trol and means for said operation governing means to cause impartation of a signalling impulse to said control via said device when in the course of a marginal stop setting operation a marginal stop to be set nears engaged relation with the counterstop.
